UNITED STATES PATENT OFFICE.

HIRAM B. CANNON, OF METUCHEN, NEW JERSEY, ASSIGNOR TO THE CARBORUNDUM COMPANY, OF NIAGARA FALLS, NEW YORK, A CORPORATION OF PENNSYLVANIA.

FLUID-HEATING FURNACE.

Application filed May 14, 1924. Serial No. 713,186.

This invention relates to apparatus or furnaces for the heating of fluids and, in the embodiment shown herein, is designed for the heating of fluids contained in and circulated through tubes arranged in operative relation to a heat-radiating combustion chamber. It is the general purpose and object of the invention to provide a fluid-heating apparatus which will utilize a high percentage of the heat resulting from the combustion of the fuel; which will enable the heating to be accomplished with a considerable reduction of furnace-volume or space over that usually required for equivalent heat capacity; and which will enable the fluid to be heated efficiently by radiant heat as well as by radiant heat in conjunction with exhaust gases. Further and more specific objects and advantages of the invention will appear hereinafter and will be realized in and through the combinations and arrangements of parts embodied in the claims.

In the drawings, Fig. 1 represents a vertical sectional view through a fluid-heating apparatus embodying the invention; and Fig. 2 a transverse sectional view taken through the central portion of the apparatus shown in Fig. 1.

Describing the various parts by reference characters, 1 denotes the shell or envelope of a furnace, the said shell being formed of heat-resistant material having low heat conductivity, enabling it to reflect heat without undue absorption thereof. Material suitable for such shell is siloel mortar, magnesia covering, and similar material. The shell is closed at its front end by a head 2 having an opening 3 for the reception of a wind box 4, which fits within the said opening and is provided at its rear end with a sleeve 5. At its rear end, the shell 1 is provided with a stack 6, for exhaust gases.

The shell 1 is shown as rectangular in cross section and is provided near the front and rear ends and near the middle thereof with inwardly-extending supporting and stabilizing frames or piers 7, the said frames or piers being seated within grooves 7^a formed in the top, bottom, and sides of the shell. Between the bottom of each frame or pier and the bottom of the groove provided therefor there extends a supporting metal strap 8, the said strap extending upwardly in and through the side walls of the shell 1.

Projecting through the front of the wind

box 4 is a burner nozzle 9, the said nozzle communicating with a T coupling 10 to which are connected a supply pipe 11, for oil or similar liquid fuel, and a pipe 12 supplying air under pressure for the purpose of atomizing the liquid fuel. Communicating with the bottom of the wind box is a pipe 13 for supplying additional or "secondary" air to the wind box.

The nozzle 9 is arranged axially with respect to the sleeve 5 and preferably extends to approximately the rear of such sleeve. This sleeve in turn fits over a neck 14 formed with and projecting from a slab 15 which closes the front end of the combustion chamber. This combustion chamber is generally of the type shown in the patent to Hiram B. Cannon, No. 1,371,774 issued March 15, 1921, and comprises, in addition to such front wall, a rear wall 16, a bottom wall 17, a top wall 18, side walls 19, and a wall 20 intermediate between the top and bottom walls and extending rearwardly from above the neck 14 to a point adjacent to but spaced from the rear wall 16 and forming a lower mixing and combustion passage A and an upper mixing and combustion passage B, with a connecting passage C around the rear end of the partition wall. The top, bottom and side walls are formed of separate slabs, the side-wall slabs 19 being seated in grooves 17 and 18^a formed in the top and bottom wall slabs respectively. The side-wall slabs are provided with seats 19^a for the partition-wall slabs 20. The various parts of which the combustion chamber is composed are made of material having great heat-absorbing and radiating qualities. The material which is preferred to use for this purpose is silicon carbide or carborundum. If desired, cement of like material as the slabs may be employed at the joints therebetween.

The combustion chamber extends from a point closely adjacent to the front wall 2 of the casing to a point adjacent to the rear wall 2^a thereof, being supported upon the bottom portions of the frames or piers 7 and having its side walls closely adjacent to the side portions of said frames.

By the construction thus far shown and described, it will be apparent that the combustion chamber is supported above the bottom of the shell 1 and that it is spaced from the sides of such shell, a considerable space being left between the top of the chamber and the up-

105

110

per portions of the frames or piers 7. The space within the shell 1 and surrounding the combustion chamber is utilized in a very efficient manner for the purpose of heating fluid.

- 5 The fluid to be heated is conducted through coils of pipe surrounding the combustion chamber. 21 denotes a supply pipe leading to the coil, the coil comprising lengths 22 of tubing extending longitudinally of the shell
- 10 and connected at their ends by bends 23, as is ordinary in heating apparatus. The tubes 22 are so arranged as to provide an outer series of such tubes surrounding the combustion chamber and jointly supported by the frames
- 15 or piers 7 and the inner wall of the shell 1, with an inner series of such pipes also surrounding the combustion chamber and mounted within the frames or piers 7, which frames or piers are also preferably of silicon
- 20 carbide or carborundum. It will be noted further that the tubes in the inner series are staggered with respect to those in the outer series, this arrangement permitting of a maximum absorption of radiant and reflected heat by
- 25 the tubes. The fluid heated within the coil is delivered to an outlet pipe 24 leading to a suitable point of use.

It will be noted that the passage B is provided with a discharge outlet D located closely adjacent to the front wall 15, whereby the products of combustion may pass upwardly and rearwardly in operative relation to the tubes 22 and be delivered to the stack 6.

The apparatus thus far disclosed may be suspended by the straps 8 from longitudinal I-beams 25 which are supported on the upper transverse members 26^a of supporting frames, the vertical members of which are indicated at 26. The upper ends of the metal straps will 40 be looped about the members 25, as indicated at 8^a.

In the operation of the apparatus thus far described oil (or other fluid fuel) will be delivered through the nozzle 9 and neck 14 into the combustion passage A, and will burn therein and in the passages C and B. For best results, the combustible fluid and air will be so controlled that the flame will travel the full length of the combustion passages, with 45 the top of the flame at the outlet D. This insures combustion throughout the entire effective length of the combustion chamber, including the three passages thereof. As a result, the chamber will be uniformly heated throughout its extent, enabling it to operate at maximum efficiency. The adjustment of the air and fuel to secure this result will be facilitated by providing the front wall 2 with a mica-covered peep hole located above 50 the outlet D. The combustible mixture within and throughout the length of the upper passage B will be heated by the lower passage A and the partition 20, facilitating the quick and complete combustion of the mixture in 55 the upper passage B.

The tubes 22 will be heated by the radiant heat of the combustion chamber as well as by the products of combustion delivered through the outlet D; but the length of the combustion chamber and the heat radiating qualities of the same are such that, by the time the flame has reached the outlet D, complete combustion of the mixture will have been obtained and the temperature of the products delivered to the outlet D will be so reduced that said products may be discharged directly against the heat absorbing tubes without injury thereto. By employing material of high heat-absorbing and radiating qualities for the frames or piers 7 the said frames or piers will be quickly heated and will transfer such heat to the tubes and to the fluid therewithin. Furthermore, the employment of a heat-resistant shell or envelope 1 of low heat conductivity enables the said shell or envelope to reflect, without great absorption, heat radiated thereto by the combustion chamber. The rays of heat directed against this envelope or casing will be reflected thereby to the tubes and absorbed by the latter. It will be noted that the outer series of tubes 22 is in close proximity to the envelope or casing 1, being partly embedded therein, as indicated; and it will be noted also that this casing is in close proximity to the bottom and sides of the combustion chamber, whereby it can operate with maximum efficiency in reflecting to the tubes the radiant heat directed thereagainst from the combustion chamber. The tubes in the space above the combustion chamber will be heated additionally by convection from the products of combustion as the latter travel from the front of the casing 2 to the flue 6 at the rear thereof.

Owing to the fact that the combustion chamber is made of slabs of silicon carbide, it will be advisable, if not necessary, to provide stabilizing members 27 beneath the joints between adjacent slabs, in addition to the frames or piers 7. These members may, and preferably will, be made of silicon carbide.

The particular structure shown herein will produce a fluid-heater of great efficiency. While I have shown my invention as embodied in a furnace of the boiler-furnace type, I do not propose to be limited to such particular embodiment.

Among the advantages obtained by the apparatus described herein are:—

- (a) Complete combustion of the fuel at very high combustion-capacity.
- (b) As much as 60 percent of the total heat resulting from the combustion of the fuel may be transmitted by radiation to the tubes or other absorbing media.
- (c) The radiant heat of the combustion chamber will be uniform throughout the length thereof, thereby eliminating localized heating.
- (d) The sensible heat of the exhaust gases

will be considerably reduced, enabling them to heat the boiler or additional objects without injury, as well as permitting the reduction of the heat-absorbing surfaces ordinarily required for absorbing heat by convection.

(e) The reduction in dimensions of the boiler or other heat-absorbing device or apparatus due to the high combustion capacity of the furnace.

(f) The elimination of severe oxidizing conditions on the heat-absorbing tubes or other media, due to the confinement of the flame within the radiating combustion chamber.

(g) The arrangement of the combustion chamber and the tubes 22 enables the tubes to constitute an absorbing screen for the radiant heat from the chamber which screen surrounds and substantially encloses the said chamber.

In order to radiate heat efficiently to the tubes or absorbent screen and to the interior of the casing 1, the refractory material of which the combustion chamber is composed should have a thermal conductivity in excess of $0.006 \text{ cal/cm}^3/\text{sec}^{\circ}\text{C}$.; and, as is well known, the thermal conductivity of silicon carbide is in excess of that expressed by this formula. Other refractories having a thermal conductivity in excess of that specified are fused aluminum oxide (Al_2O_3) and fused magnesium oxide (MgO).

Having thus described my invention, what I claim is:—

1. A fluid-heating apparatus comprising an outer casing of heat-resistant and heat-reflecting material, a combustion chamber composed principally of refractory material having a thermal conductivity in excess of $0.006 \text{ cal/cm}^3/\text{sec}^{\circ}\text{C}$. mounted within the said casing, means for heating the said chamber interiorly, and a fluid container interposed between the combustion chamber and the casing and substantially surrounding the former, the said outer casing being arranged in such proximity to the said fluid container and to the said chamber and being composed of such material as to reflect efficiently to said fluid container heat received by said casing by radiation from the said chamber.

2. A fluid-heating apparatus comprising an outer casing of heat-resistant and heat-reflecting material, a combustion chamber composed principally of refractory material having a thermal conductivity in excess of $0.006 \text{ cal/cm}^3/\text{sec}^{\circ}\text{C}$. mounted within the said casing, means for heating the said chamber interiorly, and fluid-containing tubes arranged between the said chamber and the said casing and substantially surrounding the former, the said outer casing being arranged in such proximity to the said tubes and to the said chamber and being composed of such material as to reflect efficiently to said tubes heat received by said casing by radiation from the said chamber.

3. A fluid-heating apparatus comprising

an outer casing of heat-resistant and heat-reflecting material, a combustion chamber having walls arranged to heat fluid containing tubes and composed principally of refractory material having a thermal conductivity in excess of $0.006 \text{ cal/cm}^3/\text{sec}^{\circ}\text{C}$., the said chamber being mounted within the said casing, means for heating the said chamber interiorly, and fluid containing tubes arranged between the said chamber and the said casing in such position as to be heated efficiently by radiant heat from the said chamber and by heat received by said casing from the said combustion chamber and reflected by said casing to said tubes.

4. A fluid-heating apparatus comprising an outer casing of heat-resistant and heat-reflecting material, piers of heat-absorbent and heat-radiating material mounted within said casing and projecting inwardly from the inner wall thereof, a combustion chamber of refractory material having a thermal conductivity in excess of $0.006 \text{ cal/cm}^3/\text{sec}^{\circ}\text{C}$. extending longitudinally of said casing through and mounted upon said piers, means for heating the said chamber interiorly, and fluid-containing tubes interposed between the said chamber and the said casing and mounted in the said piers, the said tubes and the said casing being so arranged with respect to the combustion chamber that the tubes will be heated efficiently by heat radiated directly thereto by the combustion chamber as well as by heat received by said casing from the said combustion chamber and reflected by said casing to said tubes.

5. A fluid-heating apparatus comprising an outer casing of heat-resistant and heat-reflecting material piers composed principally of refractory material having a thermal conductivity in excess of $0.006 \text{ cal/cm}^3/\text{sec}^{\circ}\text{C}$. mounted within said casing and projecting inwardly from the inner wall thereof, a combustion chamber composed principally of refractory material having a thermal conductivity in excess of $0.006 \text{ cal/cm}^3/\text{sec}^{\circ}\text{C}$. extending longitudinally of said casing through and mounted upon said piers, means for heating the said chamber interiorly, and fluid-containing tubes interposed between the said chamber and the said casing and mounted in the said piers, the said tubes being arranged in inner and outer series, the tubes in one series being staggered with respect to those in another series, the said tubes and the said casing being so arranged with respect to the combustion chamber that the tubes will be heated efficiently by heat radiated directly thereto by the combustion chamber as well as by heat received by said casing from the said combustion chamber and reflected by said casing to said tubes.

6. A fluid-heating apparatus comprising an outer casing, piers mounted within said casing and projecting inwardly from the in-

- ner wall thereof, a combustion chamber hav-
ing walls thereof composed principally of re-
fractory material having a thermal conduc-
tivity in excess of 0.006 cal/cm²/sec/°C. and
extending longitudinally of said casing
through and mounted upon said piers, means
for heating the said chamber interiorly, and
fluid-containing tubes interposed between the
said chamber and the said casing and
mounted in the said piers, the said piers being
composed principally of refractory material
having a thermal conductivity in excess of
0.006 cal/cm²/sec/°C.
7. A fluid-heating apparatus comprising
an outer casing of heat-resistant and heat re-
flecting material, piers mounted within said
casing and projecting inwardly from the in-
ner wall thereof, a combustion chamber ex-
tending longitudinally of said casing
through and mounted upon said piers, means
for heating the said chamber interiorly, a
fluid container interposed between the said
chamber and the said casing, U-shaped straps

mounted in the side and bottom walls of the
said casing and each extending beneath the 25
bottom of a pier, a supporting frame, and
means for suspending the said straps and the
said casing from the said frame.

8. A fluid-heating apparatus comprising an
outer casing of heat-resistant and heat-re- 30
flecting material, a combustion chamber com-
posed principally of silicon carbide mounted
with the said casing, means for heating the
said chamber interiorly, and a fluid container
interposed between the combustion chamber 35
and the casing and substantially surrounding
the former, the said outer casing being ar-
ranged in such proximity to the said fluid
container and to the said chamber and being
composed of such material as to reflect effi- 40
ciently to said fluid container heat received
by said casing by radiation from the said
chamber.

In testimony whereof, I hereunto affix my
signature.

HIRAM B. CANNON.
